UNITED STATES PATENT OFFICE.

MICHEL D. LUEHRS, OF CLEVELAND, OHIO.

MACHINE FOR THREADING BOLTS.

SPECIFICATION forming part of Letters Patent No. 268,508, dated December 5, 1882.

Application filed May 26, 1882. (No model.)

To all whom it may concern:

Be it known that I, MICHEL D. LUEHRS, of Cleveland, in the county of Cuyahoga and State of Ohio, have invented certain new and useful 5 Improvements in Machines for Threading Bolts; and I do hereby declare the following to be a full, clear, and exact description of the invention, such as will enable others skilled in the art to which it pertains to make and use 10 the same.

My invention relates to bolt-cutter heads; and it consists in the peculiar construction of the same, as will be hereinafter fully set forth and claimed.

15 In the drawings, Figure 1 is a view in longitudinal vertical section of a bolt-cutter head constructed according to my invention, showing the manner of operating the die-ring. Fig. 2 is a plan view of the die-ring-operating mechanism, showing more clearly its construction. Fig. 3 is a view in longitudinal vertical section of my bolt-cutter head, showing the manner in which the die-ring operates the dies. Fig. 4 is a plan view of the face of my cutter-head. 25 A is the head of my bolt-cutter.

B B are thread-cutting dies, which are fitted in radial slots cut in the face of the head and held in place by means of a face-plate, C.

D is a die-ring, which surrounds the head A, 30 and is adapted to slide thereon. The upper ends of the dies, which are made T-shaped, engage with T-shaped slots a a, cut in the ring D, as shown in Fig. 4. The upper ends of the dies B B are made inclined, as are also the bottom walls of the slots a a. Thus it will be seen that as the ring D is forced outward it will act to force the dies toward the center of the head A, and as the ring D is drawn back it will act to draw the dies from the center of 40 the head, the projections b b on each side of the dies engaging with the walls of the recesses c c of the slots.

E is a curved rocking lever, which is pivoted in a recess, d, cut in the outer surface of the head. (See Figs. 1 and 2.) One arm, e, of the lever E is attached to the die-ring D by means of a link, F, and an adjustable stud, G. The stud G is connected to the ring D preferably by means of the screw H, which is provided 45 with two screws having a different pitch, the coarser screw engaging in the stud G and the

finer engaging in the ring D. By thus uniting the stud G and ring D a finer and more positive adjustment can be made between the two, and it also prevents any lost motion between the parts. The object in adjusting the stud G is to lengthen or shorten the distance between the ring and arm e of the lever E, which acts to regulate the distance to which the ring D shall move forward, and hence it 55 also regulates the distance to which the dies B B shall travel toward the center of the head A. (See Fig. 3.) The rear arm, f, of the lever E is curved upward, as shown in Fig. 1, and a ring, I, which rests between the two arms e 60 and f of the lever E, acts, when it is drawn back, to depress the arm f of the lever E, which in turn acts to elevate the arm e, and also to draw said arm e backward, and with it the ring D, which is connected thereto by the link 70 F and stud G. This acts to open the dies B B, as will be readily seen. By reversing the motion of the ring I the ring D is driven forward and the dies closed.

Any suitable mechanism may be employed 75 to operate the ring I, which may be done either automatically or manually, as desired. One lever E and connection with the ring D is all that is necessary in small machines; but when it is desired, as it is in larger machines, to use 80 two levers to operate the ring D, I do not connect the adjusting-ring D to one of the studs G, but allow the screw H only to abut against the stud G, as shown in Fig. 1. By thus connecting but one of the studs to the ring D, I 85 obviate the necessity of moving each of the screws at the same time and in the same direction to prevent the straining of the parts, as would be necessary were both of the studs and screws connected. It is not, even in the larger 90 machines, necessary to connect but one of the studs to the ring, as the inclines on the dies B B, and in the upper part of the slots a a, always tend to force the ring D back.

What I claim is—

1. In a bolt-threading head, the combination, with dies and a longitudinally-sliding ring for imparting radial movement to the dies, of a two-armed lever, pivoted to the head, devices for connecting one arm of said lever to 100 the sliding ring, and devices for engaging the other arm of said lever for rocking it on its

pivotal bearing, and thereby moving the sliding ring, substantially as set forth.

2. In a bolt-threading head, the combination, with the lever E, and a means for operating said lever, of a connecting-link and an adjustable stud secured to the die-ring, substantially as shown and described.

3. In a bolt-threading head, the combination, with two levers, E E, and ring I, for operating the same, of the studs G G and die-

operating ring D, one of said studs only being connected to the said ring D, substantially as shown and described.

In testimony whereof I have signed my name to this specification in the presence of two subscribing witnesses.

MICHEL D. LUEHRS.
